UNITED STATES PATENT OFFICE

106,209

DESIGN FOR FROZEN CONFECTION

Milton Marks, Pittsburgh, Pa.

Application March 11, 1937, Serial No. 68,111

Term of patent 14 years

To all whom it may concern:

Be it known that I, Milton Marks, a citizen of the United States, residing at Pittsburgh, in the county of Allegheny and State of Pennsylvania, have invented a new, original, and ornamental Design for Frozen Confections, of which the following is a specification, reference being had to the accompanying drawing, forming part thereof.

I claim:

The ornamental design for frozen confection, as shown.

MILTON MARKS.
